CLAIM

The ornamental design for a cup with handle, as shown and described.

DESCRIPTION

FIG. 1 is a top perspective view of my new design for a cup with handle;

FIG. 2 is a top plan view thereof; and,

FIG. 3 is a cross-sectional view thereof, taken about line 3-3 of FIG. 2.

The broken line arrows in FIG. 2 show cross-sectional indicia and form no part of the claimed design.
